UNITED STATES PATENT OFFICE.

WILLIAM LIVINGSTONE, OF FLUSHING, NEW YORK, ASSIGNOR TO
HIMSELF, AND S. HARRIS POMEROY, OF CHICAGO, ILLINOIS.

PULLEY FOR SASHES OR SIMILAR PURPOSES.

SPECIFICATION forming part of Letters Patent No. 760,636, dated May 24, 1904.

Application filed April 4, 1903. Serial No. 151,190. (No model.)

To all whom it may concern:

Be it known that I, WILLIAM LIVINGSTONE, a citizen of the United States, and a resident of Flushing, in the county of Queens and State of New York, have invented certain new and useful Improvements in Pulleys for Sashes or Similar Purposes, of which the following is a specification.

My invention relates to an improvement in pulleys or wheels for sashes and other purposes, and especially to that type thereof which are made of sheet metal.

The object of the invention is to provide a light, strong, and cheap pulley in the manufacture of which the item of scrap will be substantially eliminated.

To this end the invention includes the combination and arrangement of component parts and the details of construction to be hereinafter described, and particularly pointed out in the claims.

In the accompanying drawings, which illustrate my invention, Figure 1 is a side elevation of one construction of pulley. Fig. 2 is a transverse sectional view of the same. Fig. 3 is a side elevation of the pulley with the rim removed. Fig. 4 is a side elevation of a pulley constructed in accordance with my invention provided with a locking-disk before the prongs of the latter are bent down. Fig. 5 is a similar view with the prongs of the locking-disk bent down in position. Figs. 6 and 7 are views of the blank from which the hub and arms or spokes are formed. Fig. 8 is a view of one blank rolled or pressed into tubular shape. Fig. 9 is a view showing the arms or spokes bent out. Fig. 10 is a view at right angles to Fig. 9. Fig. 11 is a view from the opposite side of Fig. 10. Figs. 12 and 13 are views of the locking-disk, and Fig. 14 is a plan view of the pulley.

The invention includes generally a sheet-metal split rim, a tubular sheet-metal hub formed of two sections arranged end to end, and arms or spokes extending radially from the inner ends of the sections, having portions for engagement with the rim. The sheet-metal rim is designated in the accompanying drawings by the letter *a* and is preferably

formed of substantially **U** shape in cross section, although this particular configuration is unimportant. Located centrally of the width of the rim and contiguous to each end of the same is a hole *a'*. These holes are spaced a distance apart equal to the arc between the reduced portions *c'* of the arms *b*², to be described, when the ends of the rim abut against each other.

In Figs. 6 and 7 two blanks B B are shown, both exactly alike, but so placed toward each other as to make the one right and the other left, from which the arms and hub of the pulley are to be built up. Each of these blanks B B is slotted lengthwise to within a distance equal half the length of the hub from the other end into four strips of equal width, three of which are of equal length, *b b b*, while the fourth, *b'*, is somewhat shorter, with a reduced portion *c'* at the end of it which is to fit into one of the holes *a a* in the rim above described. The width of these blanks B B is equal to the circumference of the contemplated hub, whose central diameter will be equal to the diameter of the hole plus the thickness of metal. The unslotted portions *b'* and *b* of the blanks B B are intended to form each one-half of the hub when rolled or pressed into circular form, while the slotted strips *b b b* and *b'* will be spread open and flattened at right angles to the hub to form four arms in the shape of a cross. So much of the arms *b b b* as exceeds the length of *b'* by *c c c* will be bent at right angles to the arms *b b b* in a line parallel to the axis of the hub, but in opposite direction thereto, Figs. 9, 10, and 13, so that the diameter from outside to outside of the opposite arms *b b* and from the outside of one arm *b* to the inner end of the reduced portion *c'* of arm *b'* will be equal to the inner diameter of the rim A², Fig. 4. All the arms *b b b* and *b'* are slightly cranked out of their normal plane about midway between the hubs and their peripheral ends for the purpose of bringing their exterior portions into the central diametrical plane of the rim. The operation of putting these parts together and completing the pulley is as follows: The reduced portion *c'* of the arm *b'* of either half of the

hub being inserted into either hole *a* of the rim from either side thereof will naturally determine the position of the other half by inserting its reduced portion *c'* of the arm *b'* 5 into the other hole *a* of the rim from the opposite side, while the ends *c c c c c c* of the other arms will come into tangential contact with the inner circumference of the rim, and as the ends *c* project from the arms *b* on one 10 side of the rim to the other side thereof it follows that when those ends *c* tangential to the inner circumference of the rim are brought into close concentric contact with the rim the corresponding arms *b* and the half-hubs *b'* will 15 be drawn close together and form a continuous hub projecting from both sides of the arms, Figs. 16 and 17, and complete the pulley.

From the above description it will appear that the two reduced portions *c'* and *c'* of the 20 arms *b'* *b'*, inserted into the holes *a a* of the rim, not only hold the same together where its ends meet and abut, but at the same time act as carriers and prevent its slipping upon the concentrical bearing-surfaces of the ends 25 *c*, while this concentric contact of the ends *c* with the rim will prevent any lateral shifting of the same and increase the rigidity of the pulley beyond that already accomplished by the fact of the arms and hub being integral. If in 30 the construction of pulleys of larger diameter additional means are required to fasten the two halves of the hub and their respective arms together nearer the center, I have provided a locking-disk *D*, having an axial opening 35 corresponding to the bore of the hub and laterally-projecting prongs *d* extending alternately in opposite directions. This disk is placed between the two halves of the hub and their respective arms, with the prongs *d* in 40 their proper position close to the arms, Fig. 4. When clenched over and against the arms, the three parts thus fastened together will appear and to all intents and purposes be a solid hub 45 with arms radiating therefrom and integral therewith.

I do not want to confine myself absolutely to either the number of arms or the precise form or details as illustrated in the drawings and herein described; but

50 What I claim, and desire to secure by Letters Patent, is—

1. In a sheet-metal pulley, the combination with the rim, of a tubular sheet-metal hub comprising two sections arranged end to end, a set 55 of arms integral with each of said sections extending radially from the inner end of the same, each of said sets comprising members of different lengths the longer of said members having angular portions engaging the rim, 60 substantially as described.

2. In a sheet-metal pulley, the combination

with the rim, of a tubular sheet-metal hub comprising two sections arranged end to end, a set of arms integral with each of said sections extending radially from the inner ends of the 65 same, each of said sets comprising members of different lengths the longer of said members having angularly-arranged portions extending in parallelism with but in an opposite direction to the hub-section carrying the same, 70 substantially as described.

3. In a sheet-metal pulley and in combination, a sheet-metal split rim having openings therethrough contiguous to each end of the same, and a tubular hub comprising two sections arranged end to end, a set of arms integral with each of said sections extending radially from the inner end of the same, each of said sets comprising members of different lengths, the longer of which have angularly- 80 extending portions engaging the rim, and the other of said members having parts interfitting said openings in the rim, substantially as described.

4. In a sheet-metal pulley, the combination 85 with the rim, of a tubular sheet-metal hub comprising two sections arranged end to end, a set of arms integral with each of said sections extending radially from the inner end of the same, portions at the outer extremities 90 of said arms engaging said rim, and a locking device interposed between said hub-sections, substantially as described.

5. In a sheet-metal pulley, the combination 95 with the rim, of a tubular sheet-metal hub comprising two sections arranged end to end, a set of arms integral with each of said sections extending radially from the inner end of the same, portions at the outer extremities 100 of said arms engaging said rim, and a locking-disk interposed between said hub-sections having portions engaging said arms, substantially as described.

6. In a sheet-metal pulley, the combination 105 with the rim, of a tubular sheet-metal hub comprising two sections arranged end to end, a set of arms integral with each of said sections extending radially from the inner end of the same, portions at the outer extremities 110 of said arms engaging said rim, and a locking-disk interposed between said hub-sections having angularly-extending prongs disposed on opposite sides thereof engaging said arms, substantially as described.

Signed at Flushing, in the county of Queens 115 and State of New York, this 7th day of March, A. D. 1903.

WILLIAM LIVINGSTONE.
